US00D567763S

(12) **United States Design Patent** (10) **Patent No.:** **US D567,763 S**
Yasumoto et al. (45) **Date of Patent:** **** Apr. 29, 2008**

(54) **FUEL CELL**

JP 2000-48849 A 2/2000

(75) Inventors: **Eiichi Yasumoto**, Kyoto (JP); **Hiroki Kusakabe**, Osaka (JP); **Hideo Ohara**, Osaka (JP)

* cited by examiner

(73) Assignee: **Matsushita Electric Industrial Co., Ltd.**, Kadoma-shi (JP)

Primary Examiner—Prabhakar Deshmukh
Assistant Examiner—Derrick Holland

(**) Term: **14 Years**

(74) *Attorney, Agent, or Firm*—Christensen O'Connor Johnson Kindness PLLC

(21) Appl. No.: **29/217,515**

(57) **CLAIM**

(22) Filed: **Nov. 17, 2004**

The ornamental design for a fuel cell, as shown and described.

(30) **Foreign Application Priority Data**

Jul. 1, 2004	(JP)	.....	2004-019832
Jul. 1, 2004	(JP)	.....	2004-019833
Jul. 1, 2004	(JP)	.....	2004-019834

DESCRIPTION

(51) **LOC (8) Cl.** **13-01**

FIG. 1 is a perspective view of top, front and right side of a fuel cell showing our new design;

(52) **U.S. Cl.** **D13/122**

FIG. 2 is a front view thereof;

(58) **Field of Classification Search** D13/118,
D13/101, 103, 199; D7/408, 409; D25/102,
D25/152, 113, 118; 204/242, 254–257; 429/19,
429/34–39, 99, 100

FIG. 3 is a rear view thereof;

See application file for complete search history.

FIG. 4 is a left side view thereof;

FIG. 5 is a right side view thereof;

FIG. 6 is a top plan view thereof, the bottom view is identical thereto;
